UNITED STATES PATENT OFFICE.

CURT MILLER, OF DAYTON, OHIO, ASSIGNOR TO THE NORTH SIDE TOOL WORKS, OF DAYTON, OHIO.

WORK-GAGE.

1,238,714.

Specification of Letters Patent. Patented Aug. 28, 1917.

Application filed March 17, 1917. Serial No. 155,404.

To all whom it may concern:

Be it known that I, CURT MILLER, citizen of the United States, residing at Dayton, in the county of Montgomery and State of Ohio, have invented certain new and useful Improvements in Work-Gages; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain improvements in machines for gaging the accuracy of work and may be termed a universal work gage. The object of the invention is to provide a gage of this character for measuring or gaging work from a standard size and for doing this work quickly and accurately.

Preceding a detail description of the invention, reference is made to the accompanying drawings of which Figure 1 is a front elevation of my improved work gage. Fig. 2 is a side elevation thereof. Fig. 3 is a top plan view of the machine. Fig. 4 is an enlarged partial sectional view of the cross head and parts mounted thereon. Fig. 5 is a sectional view on the line 5—5 of Fig. 4. Fig. 6 is a sectional view on the line 6—6 of Fig. 3, and Fig. 7 is a detail view of an anvil that may be utilized where work of a special character to be gaged renders it necessary.

In a detail description of the invention, similar reference characters denote corresponding parts in the several views of the drawings. The frame work of the machine consists of a base 2, a standard 1 extending therefrom and having a forwardly projected anvil portion 3 which supports the anvil or table 4. The frame work also consists of a vertical bearing comprising fixed clamping members 11 and 11' respectively which support a vertical adjustable standard 12 to be again referred to. The standard 12 is held in the desired position by handle screws 33 which penetrate apertured lugs of the clamping members 11 and 11' and thus the standard 12 may be held rigidly in its bearing. The portion 3 of the frame work before referred to also provides a horizontal bearing for a shaft 5 which supports standards 8—8. The standards 8—8 terminate at their lower and upper ends in clamp members 6 and 9

respectively. The lower clamps 6 receive the horizontal shaft 5 and these clamps are tightened on the shaft by means of handle screws 7. One of the clamps 9 supports a movable work holding center pin 13 and the other of said clamps 9 supports a fixed work holding or center pin 14 which cooperates with the pin 13 in holding cylindrical work or all work done on centers. The clamps 9 are tightened or loosened as the case may be by handle screws 10. The work to be gaged may be of a character to be supported on the work table 4 or may be of a character that would be better supported between the centering pins 13 and 14. The pin 13 is movable against a spring 30 which surrounds the body of said pin and is inclosed by the clamping member 9 of said pin 13. The work engaging ends 31 of the centering pins 13 and 14 are tapered to a point to facilitate a proper engagement with the work to be held thereby in gaging. Fig. 7 illustrates a form of anvil 32 that may be substituted for the fixed work holding pin 14 when work of a particular character is required to be gaged, such for example as annular pieces. Supported upon the upper end of the standard 12 is a cross head 16 one end of which lies above the work table and the work centering pins 13 and 14. The other end of said cross head 16 projects upwardly as at 28 and supports the indicating gage 27 which has a bracket 27' extending therefrom which is rigidly secured to the said part 28. The indicating gage 27 as shown in Fig. 1 contains an indicating dial having calibrations over which a pointer 34 moves. This indicator registers in the present instance the ten-thousandth part of an inch and the pointer 34 thereof is operated through the vertical movement of a pin 35 which passes through a tubular guide 36 projecting from the lower side of the indicator gage. The gage hand 34 is operated from the pin 35, the spindle of the dial hand 34 being actuated from the pin 35. These are well known features of the indicator and require no detail illustration. The lower end of pin 35 has a head 26 which at all times rests upon the head 25 on the end of the indicator lever 23. The indicator lever 23 is made of aluminum and is pivoted at 24 to the end of the cross head 16 opposite the indicator 27. Below the end 25 of said lever an adjusting screw 29 is placed for adjusting the pin 35 to bring 110

the indicator hand 34 to the proper number on the dial to indicate a standard size. Near the pivotal end of the arm 23 a vertical adjusting screw 21 is placed which passes vertically through said arm at a point adjacent to its pivot. The distance of the pivot 24 of the lever 23 from the head of the pin 15 is one-tenth the distance of the end 25 of said lever from said pin 15, therefore, the range 5 of movement of gage pin 35 is amplified in comparison with the movement of the pin 15. A horizontal locking screw 22 penetrates the end of the lever 23 and engages the screw 21 laterally to lock the same in its proper 10 adjusted position. A pin 15 actuates the gage lever 23 and is arranged below the screw 21 and is provided with a head 21' that engages the end of said screw 21. The actuating pin 15 has a coil spring 19 around 15 its body within a tubular portion 17 of the cross head 16. This spring 19 is inclosed between the head 21' of pin 15 and a nut 20 and exerts a pressure to maintain a contact 20 between the screw 21 and the head 21' of said pin 15. The lower end of the pin 15 projects in an exposed position above the table 4 and is engaged by each piece of work 25 to be gaged and which is supported upon said table or between the work centering pins 30 13 and 14. If the work is of such size or dimensions as to drive the pin 15 upwardly from its normal position, the end 25 of the lever 23 will be elevated in a multiplied proportion to the amount of upward movement 35 given the pin 15 and accordingly the indicator pointer 34 will be deflected from its set position, which position indicates the standard size for the work to be gaged to. The normal position of the pointer indicates 40 the standard or size to which the piece to be gaged is required to conform, and any plus or minus deviation from this standard of measurement may be registered upon the instrument. The pivot 24 of the indicator 45 lever 23 is provided with needle point bearings 37 which engage similar shaped cavities in the ends of a steel-hardened bushing which constitutes the pivot 24. It will be understood that before the instrument is to 50 be used the proper standard size is indicated upon the dial. This is done by placing a standard piece between the anvil or table 4 and the pin 15 or between said pin 15 and the work holding pins 13 and 14. The indicator hand 34 is then moved to the position 55 by said pin 15 to indicate the standard size of measurement and the indicator hand is then set at such position by adjusting the end 25 of the lever 23 by the screw 29.

60 Having described my invention, I claim:

1. In a work gaging machine, the combination with a standard, means on said standard for supporting work to be gaged, of a

cross head supported on said standard, an indicator or gage supported at one end of 65 said cross-head, a lever one end of which engages the operating member of said indicator and the other end of which is pivoted to said cross head, an adjusting screw adapted to engage the end of said lever so engaging 70 said indicator, a pin engaged by the piece to be gaged, and an adjustable pin in said lever in a position to be engaged by said first-named pin, said two last-named pins being adjacent to the pivoted end of said 75 lever.

2. In a work gaging machine, the combination with holding means for pieces to be gaged, of a cross head, a lever pivoted at one end to said cross head, a pin mounted in said 80 cross head adjacent to said pivot and in a position to be engaged by the pieces being gaged, an adjustable contact pin on said lever engaged by said first-named pin, an indicator or gage the operative member of 85 which is in engagement with the other end of said lever, and an adjusting screw engaged by said lever at the last-named end thereof to maintain the indicator in the normal position or to move it out of such normal position.

3. In a work gaging machine, the combination with a standard, a work table and centering pins mounted on said standard, a cross head supported on said standard, an indicator supported on one end of said cross head, a lever pivoted at one end to said cross head and the other end of which engages the operating member of said indicator, a pin near the pivoted end of said lever adapted 1 to be engaged by the work to be gaged and to actuate said lever to move the index of the indicator, and an adjusting screw in the end of said lever which engages the indicator whereby that end of the lever is adjusted 1 relative to the indicator.

4. In a machine for gaging work, the combination with means for holding work to be gaged, of a cross head, a gage indicator mounted on one end thereof, a lever pivoted 1 at one end on the other end of said cross head, the other end of said lever engaging the gage indicator, an adjusting screw engaging the end of said lever which engages 1 the operating member of the indicator, an adjusting screw penetrating said lever near its pivot and forming a point of contact for tilting the lever, and an actuating pin engaging said adjusting screw, said actuating pin being itself engaged by the work to be 1 gaged.

In testimony whereof I affix my signature, in presence of witness.

CURT MILLER.
